INTERNAL COMBUSTION ENGINE

John J. McCarthy, Malden, Mass., assignor to
Mary E. McCarthy, Malden, Mass.

Application May 13, 1940, Serial No. 334,738

22 Claims. (Cl. 123—171)

This invention relates to internal combustion engines, and more particularly to engines of the compression ignition type.

It is the primary aim and object of the present invention to provide a multi-cylinder engine in which the intake air effectively cools the cylinders and more particularly the pistons therein.

It is another object of the present invention to provide for the cooling of the hot lubricant of a circulatory lubricating system by the intake air.

It is another object of the present invention to provide an engine for aviation purposes in which a plurality of separate iron cylinders are independently mounted on the crank case of a light-weight material so that the different expansion of the cylinders and crank case does not induce any stresses in the same and interfere with the smooth performance of the movable engine parts.

It is also among the objects of the present invention to provide a manually operable brake on the propeller shaft of an aviation engine in order to enable the pilot to stop said shaft and therewith the engine itself when the engine is or has to be shut off in mid-air and the air drag on the propeller tends to revolve the latter.

Before explaining in detail the present invention, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings:

Fig. 1 illustrates, partly in section and partly in side elevation, an internal combustion engine which embodies the present invention, the section being taken substantially on the line 1—1 of Fig. 2.

Fig. 2 is a section through the engine taken substantially along the line 2—2 of Fig. 3, certain parts of the engine being omitted for the sake of clearer illustration of the crank case structure and the cylinder arrangement.

Fig. 3 is a transverse section through the engine taken substantially on the line 3—3 of Figs. 1 and 2.

Fig. 4 is a section through a perspective illustrated detail of the engine.

Fig. 5 is a section taken substantially on the line 5—5 of Fig. 3.

Fig. 6 illustrates diagrammatically a modified mode of circulating the cooling water through the various cylinders of the engine.

Fig. 7 is a fragmentary section through an outer cylinder end of an engine which embodies a feature of the present invention in a modified manner.

By preference, the present invention is shown in the drawings as being embodied in an inverted V-type engine. The reference numeral 10 designates a crank case in which a crank shaft 11 is journaled and held against axial movement in main bearings 12, provided by the crank case 10 and bearing caps 13. A suitable cover 14 is mounted on the open top of the crank case. Integral with the crank case and projecting thereinto are two rows of cylinder sleeves 15 which are arranged in a V and merge at their adjacent top ends as at 16 (Fig. 3). Preferably independently mounted as by bolts (not shown) on the crank case 10 and in coaxial alignment with the cylinder sleeves 15 thereof are separate cylinders 17 whose outer ends 18 are open and in communication with an air chamber 19. This air chamber 19 is defined by the bottom wall 20 of the crank case 10, the adjacent halves of the two rows of cylinders 17 including the ribs 21 (Figs. 1 and 3), a cover 22 suitably mounted on the open cylinder ends 18 in the manner shown in Fig. 3, and two end walls 23 and 24 of the crank case (Figs. 1 and 2). The engaging ends of each cylinder sleeve 15 and cylinder 17 are counterbored to provide an annular groove 25 (Fig. 3) into which a centering ring 26 is fitted for accurate alignment of said cylinder with said cylinder sleeve. Provided in the wall of each cylinder sleeve 15 is a plurality of intake ports 27 which communicate with an intake chamber 28. This intake chamber 28 is formed by opposite portions of the side walls 29 of the crank case, the bottom wall 20 of the crank case (Figs. 2 and 3), a partition 30 in the crank case through which the cylinder sleeves 15 extend in the manner shown in Figs. 1 and 3, and the previously mentioned end walls 23 and 24 of the crank case (Fig. 2). Each ring 26 is also provided with a plurality of intake ports 31 (Figs. 3 and 4) which register with the intake ports 27 of the respective cylinder sleeve 15 and are in communication with an internal annular groove 32 in said ring. Furthermore, each ring 26 may be rotatably mounted in its annular groove 25 and rotated by any suitable means (not shown) in order to regulate the effective area of the intake ports 27, 31.

Slidable in each cylinder 17 and cylinder

sleeve 15 alined therewith is a sleeve piston 33 whose head 34 is preferably cup-shaped and provided with a plurality of cooling ribs 35 (Fig. 3). Each sleeve piston 33 is connected with the crank shaft 11 by means of two connecting rods 36 and two wrist pins 37. More particularly, the lower ends of each pair of connecting rods 36 are forked as at 38 (Fig. 5) and straddle diametrically opposite, machined portions of the inwardly flanged, open end of a sleeve piston. These flange portions are within the confines of the outside diameter of the sleeve piston (Fig. 5) so that the center of effort of each wrist pin 37 is clearly within said confines. This secures the advantage that any bending stresses induced in a sleeve piston 33 by the connecting rods 36 thereof are effectively counteracted by the wall of the respective cylinder 17 and cylinder sleeve 15 alined therewith. Each sleeve piston 33 is furthermore provided with a multiplicity of relatively small intake openings 40 and a plurality of exhaust ports 41 which are adapted to register with the previously mentioned annular groove 32 (Fig. 3) and a circular exhaust chamber 42 in a cylinder, respectively. The circular exhaust chamber 42 of each cylinder in a row communicates through a passage 43 with an exhaust manifold 44. Slidable in each sleeve piston 33 is an opposed piston 45 which is connected with the crank shaft 11 by a connecting rod 46. The connecting rods 36 and 46 of the pistons in one cylinder row are master rods to which the connecting rods of the pistons in the other cylinder row are connected in a conventional manner.

Each cylinder 17 in a row is furthermore provided with a water jacket 47, having two ports 48 and 49 which communicate with water manifolds 50 and 51, respectively (Fig. 3). In one instance, the cooling water for the various cylinders 17 may be forced by any suitable pump 52 through conduits 53 and 53' into the manifolds 50a and 50b, respectively, from there the water passes into and through the cylinder jackets 47 to the manifolds 51a and 51b and then through conduits 54 to any conventional radiator 55 where the hot water is cooled before being drawn into the pump 52 through a conduit 56 and recirculated. The cooling water may also be circulated in the manner diagrammatically illustrated in Fig. 6, where the water is forced by a pump 52' through conduits 54' to the water manifolds 51a and 51b, and from there into and through the cylinder jackets 47 and then through the manifolds 50a and 50b and conduits 53'' and 53''' to a radiator 55' in which the water is effectively cooled before being returned to the pump 52' through a conduit 56'.

Mounted in the wall of each cylinder 17 is at least one fuel injector 60 which communicates through a conduit 61 with any conventional fuel plunger pump 62 which is mounted on the crank case 10. The plunger 63 of each fuel pump 62 along a cylinder row is operated by a cam lobe 64 of a cam shaft 65 which is suitably journaled and held against axial movement in the crank case and suitably driven in timed relation with the crank shaft rotation. When the opposed pistons in any cylinder are substantially in their inner dead center position as shown in one instance in Fig. 1, an exhaust port 41 of the sleeve piston registers with the fuel injector 60 through which fuel is then forced into the combustion chamber 66 (Fig. 1) for a combustion.

The previously mentioned air chamber 19

communicates with the atmosphere through a plurality of conduits or scoops 18 which extend through the cover 22. More particularly, a scoop 18 is secured by a spider 71 (Fig. 3) to the outer open end of each cylinder 17 and extends into close proximity to the bottom of the cup-shaped head of the sleeve piston therein when the latter is in its outermost position (Fig. 3) so that the incoming air flows first past the cooling ribs 35 in said piston head and absorbs some of the heat thereof before entering the air chamber 19.

Mounted on the end wall 23 of the crank case is a twin supercharger 75 (Figs. 1 and 2) having a common inlet 76 which communicates with the air chamber 19 through an opening 77 in said end wall 23 (Figs. 1 and 3). Two rotary impellers 78 and 79 of the supercharger draw air from the chamber 19 through the common inlet 76 into passages 80 and 81, respectively, and force said air into the intake chamber 28 through discharge chambers 82 and 83, respectively, of the supercharger and admission ports 84 and 85, respectively, in the end wall 23 of the crank case (Fig. 2). The rotary impellers 78 and 79 of the supercharger may be driven in any suitable manner from the crank shaft 11. The present invention being shown embodied in an aviation engine having a driven propeller shaft 86, the rotary impellers 78 and 79 are preferably driven from the propeller shaft 86 in the following manner. The impellers are mounted on a suitably journaled sleeve 81 (Fig. 1) whose one-end is provided with a small gear 82 which meshes with a larger gear 83 on a suitably journaled stub shaft 84 that carries another gear 85 which meshes with a larger gear 86, mounted on a suitably journaled shaft 87 which passes through the sleeve 81 and is splined at 88 to the propeller shaft 86. In this manner, the rotary impellers 78 and 79 of the supercharger are driven at increased speed from the propeller shaft 86. As best shown in Fig. 2, the air admission ports 84 and 85 to the intake chamber 28 are in line with the two rows of cylinder sleeves 15, and the cylinder sleeves 15 of each row are provided with baffles 100 which preferably decrease in height on consecutive cylinder sleeves. These baffles 100 are adapted to direct the admitted supercharged air substantially uniformly around the peripheries of the sleeve pistons so that all the intake ports 27 therein receive approximately the same amount of air. The cylinder sleeves most remote from the air admission ports 84 and 85 to the intake chamber 28 require no baffles as the air is repelled by the adjacent end wall 24 of the crank case and thus forced around said cylinder sleeves.

Mounted on the end wall 23 of the crank case 10 is a hood 100a which houses the supercharger 75 and a drive between the crank shaft 11 and the propeller shaft 86, the latter being suitably journaled at 101 and 102 in the hood 100a. The drive between the crank shaft 11 and the propeller shaft 86 comprises a gear 104 whose hub 105 is journaled in suitable bearings 106 and splined at 107 to the adjacent end of the crank shaft 11, and a larger gear 108 which is mounted on the propeller shaft 86.

The present engine is lubricated by a circulatory lubricating system which comprises a lubricant reservoir 110 (Figs. 1 and 3) and means for circulating the lubricant from the reservoir to the moving engine parts to be lubricated and back to the reservoir. For the sake of brevity and

because it forms no part of the present invention, the lubricant circulating means is not shown in the drawings. It is instead deemed sufficient to explain that lubricant from the reservoir 110 is forced in a conventional manner to the crank shaft 11 which is suitably drilled to conduct the lubricant to the connecting rods 38, 46 and the main bearings 12 from where the lubricant escapes to the cheeks 11a of the crank shaft. The lubricant is then thrown off the cheeks 11a of the crank shaft and into an auxiliary basin 111 which is formed in the crank case and whose bottom is the previously described partition wall 30 through which the cylinder sleeves 15 extend in the manner shown in Figs. 1 and 3. Some of the lubricant will also splash against the walls of the cylinder sleeves 15 and lubricate the sliding pistons 33, 45. The ends of the auxiliary basin 111 communicate with the ends of the lubricant reservoir 110 through cored-out passages 112 in the crank case 10 (Figs. 1 and 2). The lubricant in the auxiliary basin 111 is thus immediately returned to the reservoir 110 through either one of the passages 112 regardless of the inclination of the engine when the same is, for instance, used in an airplane. As best shown in Figs. 1 and 3, the lubricant reservoir 110 is located in the air chamber 19 and preferably suspended from the bottom wall 20 of the crank case between the two cylinder rows.

In operation, atmospheric air is drawn by the supercharger 75 into the air chamber 19 through the scoops 10. The admitted air flows first into the outer cylinder ends 18 and effectively cools the sleeve piston heads 34 which become very hot as they are in close proximity to the exhaust ports 41 in the sleeve pistons. The air then flows through the chamber 19 in heat-exchange relation with the water manifolds 50 and the lubricant reservoir 110, with the result that the cooling water as well as the lubricant become cooled. The water manifolds 50 as well as the lubricant reservoir 110 may be provided with ribs 115 for a more efficient heat exchange. It appears also from Figs. 1 and 3 that substantially one-half of the circumference of the water jacket of each cylinder is in heat-exchange relation with the intake air in the chamber 19, whereby the cylinders are further cooled. From the chamber 19, the air is drawn into the supercharger 75, and the supercharged air is expelled into the intake chamber 28 to be admitted at the proper times through the intake ports 27, 31 and 40 into the cylinder chambers 120 which are formed by each pair of opposed pistons 33, 45. At the proper moments injection of fuel into the combustion chambers 66 (Fig. 1) takes place. To provide for straight-through scavenging of the cylinder chambers 120 by the intake air and also for retention of sufficient combustion air in said cylinder chambers, the exhaust-controlling sleeve pistons 33 have preferably a lead over the pistons 45 so that the exhaust ports 41 of said sleeve pistons move out of registry with the exhaust passages 42 before the intake ports 27, 31 are covered jointly by the pistons 33, 45. The annular grooves 32 in the centering rings 26 (Figs. 3 and 4) serve as surge passages or chambers through which the intake air is substantially uniformly distributed around the sleeve pistons 33 and the intake openings 40 therein.

The cylinder sleeves 15 are provided around their circumference with a multiplicity of minute ducts 121 which provide communication between the supercharged air in the intake chamber 28

5 and the interior of the cylinder sleeves 15. These ducts 121 are normally covered by the sleeve pistons 33 and are uncovered when the intake openings 40 in the sleeve pistons register with said ducts as shown in one instance in Fig. 1, whereupon fine air jets issuing from the ducts 121 blow any lubricant from the intake openings 40.

10 The crank case 10 is cast in one piece and each of the cylinder rows mounted thereon may be cast in one block in cases where the weight of the engine is of no primary importance. However, since the disclosed engine is particularly adaptable for aviation purposes, its total weight has to be as small as possible. To this end, at least the 15 crank case 10 is made of a light-weight material such as aluminum, while the cylinders 17 are cast of iron. As such a light-weight material as aluminum has a larger coefficient of expansion than cast iron, the cylinders 17 are cast separately and are independently mounted on the crank case in the previously explained manner. In this way, the expansion of the light-weight crank case does not induce any stresses in the cylinders 17 since the same may individually expand with said crank case. As a consequence, the smoothly 20 performing driving connection between the pistons 33, 45 and the crank shaft 11 is never disturbed by the different expansion of the crank case 10 and cylinders 17 and the latter are always 25 retained in perfect alignment with their respective cylinder sleeves 15 by the centering rings 26.

30 As previously mentioned, the cooling water for the various cylinders may be circulated in the manner illustrated in Fig. 3 or in the manner illustrated in Fig. 6, depending upon the amount of heat permissible in the intake air for an efficient combustion.

35 Whereas the engine so far described has a sleeve piston in each cylinder, Fig. 7 shows a modification in which only one piston (not shown) reciprocates in a sleeve 131 in the cylinder 130. The sleeve 131 is reciprocated in the same manner as the sleeve pistons 33 in the engine shown in Fig. 3 in order to provide communication between the exhaust ports 132 in said sleeve and the circular exhaust passages 133 in said cylinder. The cylinder head 134 is cup-shaped and provided with cooling ribs 135 and the sleeve 131 is guided between said cylinder head 134 and the cylinder 130. An air admission scoop 136 extends considerably into the cup-shaped cylinder head 134 so as to conduct the admitted air first against said cylinder head before it flows into the air chamber 137. Thus, each piston head 134, which constitutes one of the hottest spots of the engine due to its close proximity to the exhaust ports 132, is effectively cooled by the admitted air.

40 Mounted on the propeller shaft 80 within the hood 100a is a conventional hydraulic brake 140 which enables the pilot of the aircraft to completely stop the engine after the same is or has to be shut off in mid-air due to engine trouble or for some other reason, and to prevent the air drag on the propeller to turn the engine over. Hence, the brake 140 will, for instance, effectively 45 prevent further damage to a damaged engine after the same is shut off and while the aircraft is still in the air. The brake 140 comprises the usual drum 141 which is mounted on the propeller shaft 80 and is adapted to cooperate preferably with two opposite brake shoes 142 which are pivotally mounted on a bracket 143 in the hood 100a. The brake shoes 142 are normally

urged toward each other and out of braking engagement with the drum 141 by means of a spring 144, while opposite pistons in the usual master cylinder 145, which is mounted on a bracket 146 in the hood 100a, force said brake shoes into braking engagement with the drum 141 when the fluid pressure in the master cylinder is increased in the usual way by a remote foot pedal.

I claim:

1. In an internal combustion engine, the combination of a plurality of cylinder members having intake and exhaust ports near their inner and outer ends, respectively; a sleeve member slidable in each cylinder member and constituting together with the latter a unit and having intake and exhaust ports adapted to register with the corresponding cylinder ports; a piston slidable in each sleeve member and adapted to cover and uncover the intake ports therein; a head on the outer end of a member of each unit forming together with the sleeve member of said unit and the piston therein a cylinder chamber; a first chamber separated from all cylinder chambers by said heads; a second chamber surrounding the intake ports of all cylinder members; and means providing communication between said first and second chamber, said first chamber having air admission ports so arranged that said heads are in heat-exchange relation with the admitted air.

2. The combination in an internal combustion engine as set forth in claim 1, in which said means is a supercharger whose intake and exhaust sides communicate with said first and second chamber, respectively.

3. The combination in an internal combustion engine as set forth in claim 1, further comprising a circulating lubricating system including a lubricant reservoir located in said first chamber in the path of flow of the admitted air.

4. The combination in an internal combustion engine as set forth in claim 1, further comprising a cooling jacket on the cylinder members, a pump, and means providing a circuitous path for a cooling liquid between the pump and jacket and including a conduit leading from the jacket to the pump and extending in said first chamber in heat-exchange relation with the admitted air.

5. The combination in an internal combustion engine as set forth in claim 1, further comprising a jacket on each cylinder member, a pump, and means providing a circuitous path for a cooling liquid between the pump and each jacket and including a manifold connecting each jacket with the pump and extending in said first chamber in heat-exchange relation with the admitted air.

6. The combination in an internal combustion engine as set forth in claim 1, in which said means is a supercharger whose intake and exhaust sides communicate with said first and second chamber, respectively, and baffles are provided in said second chamber for directing the supercharged air to the intake ports of all cylinder members.

7. In an internal combustion engine, the combination of a plurality of cylinders open at both ends and having intake and exhaust ports near its inner and outer end, respectively; opposed pistons in each cylinder, one being a sleeve piston having intake and exhaust ports adapted to register with the corresponding cylinder ports; a first chamber into which the outer ends of all cylinders open; a second chamber surrounding

the intake ports of all cylinders; and means providing communication between the chambers, said first chamber having air-admission ports so arranged that said outer cylinder ends are in the path of flow of the admitted air.

5 8. The combination in an internal combustion engine as set forth in claim 7, in which said air admission ports extend into said outer cylinder ends so that the admitted air flows first into the latter and then into said first chamber.

9. In an internal combustion engine, the combination of two rows of cylinders arranged in a V, each cylinder being open at both ends and having intake and exhaust ports near its inner and outer end, respectively; opposed pistons in each cylinder, one being a sleeve piston having intake and exhaust ports adapted to register with the corresponding cylinder ports; a first chamber surrounding the intake ports of all cylinders; a second chamber laterally confined between the portions of the cylinder rows extending from said first chamber to the outer cylinder ends, and said outer cylinder ends opening into said second chamber; and a supercharger at one end of the cylinder rows having its intake and discharge sides in communication with said second and first chamber, respectively, and said second chamber having air admission ports so arranged that said outer cylinder ends are in heat-exchange relation with the admitted air.

10. The combination in an internal combustion engine as set forth in claim 9, further comprising a separate jacket on each cylinder, a pump, and means providing a circuitous path for a cooling liquid between the pump and each jacket and including a manifold connecting each jacket with the pump and extending in said second chamber in heat-exchange relation with the admitted air.

11. The combination in an internal combustion engine as set forth in claim 9, further comprising a jacket on each cylinder, a radiator, a pump having its intake side connected with the discharge side of said radiator, a first manifold connecting each jacket with the intake side of said radiator and extending in said second chamber in heat-exchange relation with the admitted air, and two manifolds extending alongside the cylinder rows outside of the V and connecting the jackets of said cylinder rows, respectively, with the discharge side of the pump.

12. The combination in an internal combustion engine as set forth in claim 9, further comprising a jacket on each cylinder, a radiator, a pump having its intake side connected with the discharge side of said radiator, a first manifold connecting each jacket with the discharge side of the pump and extending in said second chamber in heat exchange relation with the admitted air, and two manifolds extending alongside the cylinder rows outside of the V and connecting the jackets of said cylinder rows, respectively, with the intake side of the radiator.

13. In an internal combustion engine, the combination of a cylinder having an annular recess in its cylindrical wall and a first intake port opening into said recess; a ring rotatable in said recess and being flush with the cylinder wall and having an internal peripheral groove and another intake port providing communication between said first port and groove; and opposed pistons in the cylinder, one being a sleeve piston having intake openings which are distributed around its sleeve and adapted to communicate with said groove, and the effective area of said ports being varied on turning said ring.

14. In an internal combustion engine, the combination of a crank-case having a first cylinder member integral therewith, a second cylinder member secured to said first member in axial alignment therewith and forming together with the latter one cylinder, the adjacent ends of said members being countersunk to form an annular groove in the cylinder wall and at least one of said members having a first intake port opening into said groove; and a ring rotatably mounted in said groove and having another intake port in communication with said first port, said ring accurately aligning said members and, on being turned, varying the effective area of said ports.

15. The combination in an internal combustion engine as set forth in claim 14, further comprising opposed pistons in the cylinder of which one is a sleeve piston having intake openings distributed around its sleeve, and said ring having in its inner surface an annular groove into which said other port opens and with which said intake openings are adapted to communicate.

16. In an internal combustion engine, the combination of a crankcase having a plurality of first cylinder members integral therewith; other separate cylinder members of a material having a different coefficient of expansion than the crankcase material and being separately secured to said first members in axial alignment with the same, each pair of aligned members forming one cylinder, and the adjacent ends of said members being countersunk to form an annular groove in the cylinder wall and at least one member of each pair having a first intake port in communication with the countersink thereof; and a ring mounted in each of said cylinder grooves and having an intake port in communication with said first port, said rings maintaining said members accurately aligned at all temperatures.

17. The combination in an internal combustion engine as set forth in claim 16, in which said rings are rotatably mounted in said cylinder grooves to permit variation of the effective area of said intake ports.

18. The combination in an internal combustion engine as set forth in claim 16, further comprising opposed pistons in each cylinder of which one is a sleeve piston having a plurality of intake openings distributed around its sleeve, and each of said rings having in the inner wall an annular groove into which its intake port opens and with which the intake openings of a sleeve piston are adapted to register.

19. In an internal combustion engine, the combination of a cylinder having intake and exhaust ports in its wall; opposed pistons in the cylinder of which one is a sleeve piston having intake and exhaust ports adapted to register with the corresponding cylinder ports, the intake ports in said sleeve piston being nearer the open end of the sleeve and cleared by the other piston when both pistons are substantially in their innermost position; and means for lubricating the sliding surfaces of both pistons, said cylinder having a plu-

rality of minute holes in its wall providing communication between a source of compressed air supply and the intake ports in the sleeve piston when the pistons are substantially in their innermost position whereupon compressed air escaping through said holes blows lubricant from the intake ports in said sleeve piston.

20. In an internal combustion engine, the combination of a cylinder having intake and exhaust ports in its wall; a chamber surrounding the intake ports; a supercharger delivering compressed air to said chamber; opposed pistons in the cylinder of which one is a sleeve piston having intake and exhaust ports adapted to register with the corresponding cylinder ports, the intake ports in said sleeve piston being a multitude of small intake openings which are nearer the open end of the sleeve than the exhaust ports therein and cleared by the other piston when both pistons are substantially in their innermost position; and means for lubricating the sliding surfaces of both pistons, said cylinder having a multitude of minute holes in its wall providing communication between said chamber and said intake openings when the pistons are substantially in their innermost position whereupon compressed air escaping through said holes blows lubricant from said intake openings.

21. In an internal combustion engine, the combination of a plurality of cylinder members having intake and exhaust ports near their inner and outer ends, respectively; a sleeve member slidable in each cylinder member and constituting together with the latter a unit and having intake and exhaust ports adapted to register with the corresponding cylinder ports; a piston slidable in each sleeve member and adapted to cover and uncover the intake ports therein; a head on the outer end of a member of each unit forming together with the sleeve member of said unit and the piston therein a cylinder chamber; and another chamber separated from all cylinder chambers by said heads and communicating with the intake ports of all cylinder members and having air admission ports so arranged that said heads are in heat-exchange relation with the admitted air.

22. In an internal combustion engine, the combination of two rows of cylinders arranged in a V, each cylinder being open at both ends and having intake and exhaust ports near its inner and outer end, respectively; opposed pistons in each cylinder, one being a sleeve piston having intake and exhaust ports adapted to register with the corresponding cylinder ports; a first chamber surrounding the intake ports of all cylinders; and a second chamber to the interior of which portions of all cylinders including their outer ends are exposed, said second chamber having air admission ports so arranged that said exposed cylinder portions are in heat-exchange relation with the admitted air.

JOHN J. McCARTHY.
